CLAIM

The ornamental design for a firearm sight, as shown and described.

DESCRIPTION

FIG. 1 is a front upper left perspective view of a firearm sight, showing my new design;

FIG. 2 is a front elevation thereof;

FIG. 3 is a rear elevation view thereof;

FIG. 4 is a left side elevation view thereof;

FIG. 5 is a right side elevation view thereof;

FIG. 6 is a top plan view thereof; and,

FIG. 7 is a bottom plan view thereof.

The broken lines in FIGS. 1-7 form no part of the claimed design and include dot-dashed lines that define the bounds of the claimed design and dashed lines that illustrate portions of the firearm sight that form no part of the claimed design.

1 Claim, 7 Drawing Sheets(56)
